UNITED STATES PATENT OFFICE.

WILLIAM N. WHITELY, JR., OF SPRINGFIELD, OHIO.

IMPROVEMENT IN HARVESTERS.

Specification forming part of Letters Patent No. **63,192**, dated March 26, 1867.

To all whom it may concern:

Be it known that I, WILLIAM N. WHITELY, Jr., of Springfield, in the county of Clark and State of Ohio, have invented a new and useful Improvement in Harvesters; and I do hereby declare the following to be a full, clear, and exact description of the same, reference being had to the accompanying drawings, in which—

Figure 1 is a perspective view of my machine. Fig. 2 is an elevation of the inner side of the frame of the machine, showing the mechanism of the same. Fig. 3 is a plan view of the machine, the reel, reel-post, and driver's seat being removed. Fig. 4 is an elevation of the open bracket supporting the reel. Fig. 5 is an elevation of the foot of the rake-guide, the inner shoe, and one of the guard-fingers, showing the position of the cutter-bar above the finger-bar. Fig. 6 is an elevation of the outer side of the machine. Fig. 7 is an elevation showing the mechanism for driving the rake and the device for throwing it in and out of gear.

The nature of my invention will appear from the following description. That others may understand its construction and operation, I will more particularly describe it.

The main frame A, I cast in a single piece with the requisite bearings properly disposed. Near the forward end of the main frame are the boxes and bearings for the main driving pinion-shaft B. The sector-plate C is hung upon this pinion-shaft and has a free vertical movement upon it as a center of motion, the rear end of the sector-plate being confined and guided by the grooved curved standard D, which is secured at its base to the main frame, near its rear end, as shown in Fig. 6. The standard D is curved so as to conform to the arc of a circle whose center is the center of the pinion-shaft B, so that the sector-plate C, as it rises and falls, shall at all times be confined at its rear end by the groove in the standard.

From the front end of the machine rises a plain curved standard, E, which, curving backward, passes the head of the standard D, and is secured to it by a screw or otherwise, so that the upper end or head of the standard D is supported thereby.

The standard E extends backward beyond

the head of the standard D, and then forms a brace and support to the reel-post F, which is secured to it and to the standard D near its base. To the standard E the driver's seat G and the foot-board H are secured, as shown.

Upon the outer side of the main frame is the arch I, secured by suitable feet to the main frame, as shown in Fig. 3. To the highest point of this arch is secured a suitable bearing for the axle of the rake's driving-wheel J. The axle of J is about vertical to the axle B, and its outer face, near the periphery of the pitman-head of the rake's pitman K, is secured by a ball-and-socket joint.

The pinion-shaft B has upon each end a pinion, the main driving-wheel's pinion L upon its outer end, and the rake's driving-pinion M on its inner end, and a bevel-gear wheel, N, near its center, which gear drives the cutter's crank-shaft, and it also has between the bevel-gear N and the pinion M the reel's driving-pulley O, the entire movements of the mechanism of the machine being effected through this shaft.

The main bearing and driving wheel P of the machine has its axle secured to the sector-plate C near its rear end, and therefore when the said sector-plate moves up and down upon its center of motion the height of the axle of the wheel P in respect to the frame A is changed, and the height of the frame A from the ground may be thus regulated at will. The bearing-wheel P is also an internal gear-wheel, and meshes with the pinion L, which, being moved upon the same axis with the sector-plate C, and therefore upon the center of motion upon which the bearing-wheel itself moves up and down, it follows that the axis of the pinion L is at all times at the same distance from the axis of its driving-wheel, and they must therefore always be in mesh.

The pinion L is loose upon its shaft, and is provided with an ordinary clutch-collar and shipper, Q, so that by slipping the pinion end-wise upon its shaft a sufficient distance it may be brought up to the clutch-pin, or released from it, according as it is desired to have the mechanism in motion or otherwise.

The shipper Q is pivoted to a stud, R, projecting from the side of the sector-plate C, and has a stop-stud, S, also projecting from the side of the sector-plate, by which the shipper

may be held in the desired position to keep the mechanism in or out of gear. A lever, T, is also attached to the sector-plate C, and by it the machine may be raised or lowered in respect to the axle of the bearing-wheel, as, when the pin or other fastening holding the sector-plate C and standard D in position with respect to each other is removed and the hand placed upon the lever T, it becomes a lever of the first order, with a fulcrum at the axle of the wheel P, so that if pressure be applied to the lever T the axle B at its other end will be caused to rise, and the main frame A will likewise rise with it.

The wheel J is an internal gear-wheel and always in mesh with the pinion M, which, like the pinion L, is loose upon the shaft, and is thrown up to or away from the clutch-pin m by the shipper U, secured to the stud V, projecting from the arch I. The pin m slips into a vertical groove or slot cut across the face of the pinion M when said pinion is brought up to it by the shipper for the purpose of being thrown into gear.

The shipper U does not communicate directly with the pinion M, because the axle of the wheel J being vertical to the axis of the pinion M the shipper U would be thrown too far forward to be convenient if it were arranged to act directly upon the pinion M, and, also, it is necessary to avoid the axle of J. I therefore step the lower end of U in a hole or cavity in the upper side of the short pivoted lever W, which, being pivoted at its front end to the main frame, and being forked at its rear end to fit the clutch-collar of the pinion M, causes the said pinion to slide back or forth when pressed by the lever U.

The bevel-gear N meshes with the bevel-gear X upon the forward end of the cutter's crank-shaft Y, which lies along the upper surface of the outer side bar of the main frame, and is secured in suitable boxes fastened by bolts thereto. At the rear end of the shaft Y is the cutter's pitman-crank.

The rear end of the main frame is prolonged downward and backward in a comparatively thin flange, Z, which serves as a shield to protect the crank of the shaft Y, and also at its inner rear corner as an attachment for the inner shoe, A', of the cutting apparatus.

The finger bar B' is of ordinary construction and attachment, and at its outer end is a shoe that does not differ materially from those hitherto presented in patent applications, except in the manner of attaching the divide-board and grain-wheel. The cutters are secured to the under side of the cutter-bar C', and are arranged and placed entirely above and clear of the finger-bar B', resting, in fact, upon strips d projecting forward from the guide-blocks D', as shown in Fig. 5, so that there is no danger of clogging under the cutter-bar, and the friction is also materially reduced by being confined to a few isolated points. The outer shoe, E', is provided with a broad vertical flange, F', and the divide-

board G' is secured to the inner surface of this flange by screws or other suitable means. To the rear end of the shoe E' is attached, by a vertical hinge, H', the caster grain-wheel I'. I prefer to arrange the grain-wheel in this way, because in backing the machine, as it is sometimes necessary to do, the grain-wheel will then follow in the manner of any ordinary caster-wheel, and for that reason its operation will be more satisfactory.

In order that I may be enabled to adjust the outer end of the cutting apparatus to any required height of cut, I must provide a means of raising or lowering the grain-wheel I' in respect to the platform of the machine; and to do this I have employed between the hinge H' and the wheel I' a jointed arm, J', provided with a radially-serrated disk, K' L', on each part, and these disks I clamp together by a bolt through their center, the radial serrations meshing into each other when drawn closely by the bolt, so that it is impossible for either to turn upon its axis without affecting the other; and as the disk L' is a part of that portion of the arm J' which is hinged to the shoe at H', and therefore can have no movement except in a horizontal direction upon the pivot of H', it follows that the disk K' can have no other movement except a horizontal one; but when the clamping-bolt through the centers of the disks K' and L' is loosened, then the disk K', with the wheel I' attached, may be turned on its axis, and the wheel I' moved to a position more or less vertical to the joint K' L', and therefore the cutting apparatus will at its outer end be raised more or less from the ground.

An inward projection, M', upon the inner side of the outer shoe embraces or covers the outer end of the cutter-bar when in its inner reciprocation, so that none of the standing crop can get behind or opposite the end of the cutter-bar to obstruct its return outward.

Upon the inner shoe, A', is mounted the forward end of the rake-guide and arch N'. This mounting is upon two stout feet, O', one of them resting upon the shoe forward of the cutters, and the other resting upon the same just back of the cutters. A screw through each foot into the shoe secures this end of the rake-guide very securely.

Bolted to the inner shoe, A', and projecting inward therefrom in a line with the finger-bar B', is the flat bar or plate P'. The rake Q' is pivoted to the extreme end of this plate, as shown in Fig. 3, by a ball-and-socket joint, which permits said rake to move horizontally back and forth, but permits it also to have a vertical movement upon the same center, as is necessary in raising the rake up to return to the front of the platform over the heads of the falling grain. This joint is plainly shown in Figs. 2 and 6. The extreme end of the plate P' also serves as an attachment for the brace R', which connects it to the rear end of the rake-guide N' for the purpose of supporting and steadyng the same.

It will be observed that the rake-guide N' has no connection with the platform, but is entirely independent therefrom, receiving its entire support from the feet O' O' and the brace R'. The guide N' is bent horizontally in the arc of a circle, whose center is the center of the joint upon which the rake Q' moves in its reciprocations. Its horizontal surface is parallel with the surface of the platform, or so that as the rake sweeps backward over the platform the weight thereof shall rest upon the guide-rail N' and not upon the points of the rake-teeth.

In order that the rake may be raised up from the platform when it is being returned to the cutters, I provide the arch S', which is secured at each of its ends to the corresponding ends of the guide N'. The arch S' is considerably broader through its central portion than at its ends, and is constructed with the offsets T' T' at each end of said broad portion.

As will be seen by reference to Fig. 2, the front portion of the arch rises abruptly to a much greater height from the rail N' than does the corresponding rear portion. The front offset T' is therefore much higher from the rail than the rear offset, so that when the rake is being drawn forward, held up, and supported by the arch S', it may be allowed to drop vertically upon the platform when it has reached the farthest forward point of its reciprocation. In order to secure this compound movement of the rake I attach to its upper side, outside of the arch S', the latch U', which is so adjusted that when the rake is pushed backward the end of the latch-bolt is pressed down by the under surface of the arch S' until the rear offset T' is reached, beyond which the narrow portion of the arch is so far removed from the center upon which the rake moves that it is beyond the reach of the latch-bolt.

The distance vertically between the rear offset T' and the rail N' is considerably less than the vertical distance between the latch-bolt U' and the lower surface of the rake-head, and it therefore follows that after the rake has passed the rear offset T' and is being returned again for another stroke the latch-bolt U' will come in contact with the upper surface of the arch at the rear offset T', and will therefore in its further forward movement of the rake ride upon and be raised up from the platform by said arch until the front offset is reached, when the latch will pass off from the arch and the rake will drop upon the platform.

In order to give additional steadiness to the stroke of the rake and to permit or enable the pitman K to withdraw the rake from the farthest point of its reciprocation with more ease than hitherto, I attach rigidly to the rake-head, just beneath the latch U', a flange or plate, V', and to the outer edge of this flange or plate I pivot the pitman K. The advantage of this arrangement rests in the fact that it places the center of the joint between the

rake and its driving-pitman at a distance from the rake, thus adding a certain amount of leverage in favor of additional steadiness and removing the line of draft of the pitman at a distance from the center upon which the rake moves, and therefore enabling the pitman to withdraw the rake with less power than would be required if the line of draft were more nearly coincident with the centers of motion.

The forward end of the pitman K is provided with a screw-thread, and screws into the pitman-head, as shown in Figs. 2 and 3, so that the stroke of the rake may be thereby accurately adjusted by lengthening or shortening the pitman by screwing it a greater or less distance into the pitman-head. A set-nut to jam against the end of the pitman-head secures it against any undesired change.

The reel preferred with my machine is of the class known as "overhung." Its form and construction are shown in Figs. 1, 2, and 4. The reel-post F has fitted to it so as to slide freely up and down thereon a sleeve, W', which may be set and maintained at any particular point by the set-screw X'. The open bracket Y' is secured to the two extremities of the sleeve W', and serves as a support to the reel-shaft by enabling me to place one of the bearings for said shaft so far from the other that the driving-pulley Z' may be between the two bearings, as is shown in Fig. 4. On the outer end of the shaft I place a branched head, A'', having three or more arms, to which as many wing-staves for the wings of the reel are secured. The wings of the reel are long enough to sweep over the outer divide-board, as shown in red in Fig. 3, so that none of the standing crop may slip past the end of the reel and therefore fail to be cut.

The reel is driven by a belt from the pulley O on the main pinion-shaft, and in order that the slack consequent upon lowering the rake upon the reel-post may be taken up, the tightening-pulley B'' is adjusted to give the required tension to the reel-belt. The pulley B'' is pivoted to an adjustable arm, C'', which may be set and secured at any angle to give the required pressure upon the belt.

The tongue D'' is attached to the main frame A by means of the plate E'', which is cast in such form as to embrace the forward end of the main frame between lugs F'' F'', which project backward from the base of the said plate. A bolt, G'', passes through the lugs F'' F'' and through proper holes in the main frame, so that the tongue-plate E'' is hinged thereby to the said main frame.

At the forward end of the tongue-plate E'' is the disk H'', which has two studs projecting upward from opposite sides upon its upper surface. The disk I'' is fitted to the top of the disk H'', and has its edge notched, so that when in place the notches pass over the studs of the disk H''.

The double-tree J'' is secured to the disk I'' by flanges and by the central pivot-bolt K'', and the motion of said double-tree upon its

pivot-bolt is limited by the studs and notches of the two disks.

In order to enable the attendant to control the height of the forward end of the machine, it is necessary to provide some means by which he can raise and lower the tongue at pleasure and to hold it at any desired point. I therefore provide the lever L'' , which I pivot at its lower end to the curved standard E , and connect it to the double-tree pivot-bolt by the bar M'' , and thus raise or lower the tongue in respect to the frame, according as the upper end of the lever is drawn back or thrust forward.

To hold the lever at any desired point the rack N'' is provided, between the teeth of which the lever is thrown by the spring O'' , and there held either forward or backward, as desired.

The operation of my machine will have been apparent from the foregoing description, but the following recapitulation of its functions may not be out of place: Either end of the machine may be raised or lowered, as desired, independent of the opposite end. By means of the clutch-lever U the rake may be thrown out of gear at any point of its stroke, and the attendant may therefore control the size of the gavel thrown off by the rake. By using an internal gear at J the rake's driving-wheel will move in the same direction as the master-wheel, and the pitman-head will rise at the same moment with the rake, so that the rake-pitman will work more nearly level, and con-

sequently with less friction and labor, than would be the case did this driving-wheel revolve in the opposite direction. By means of the compound levers L'' and M'' the height of the forward end of the machine is controlled with great ease and nicety. By removing the platform, outer divide-board, reel, and rake the machine is converted into a mower, and may be so adjusted as to cut as close to the ground as desired.

The caster-wheel may be used when mowing, or not, as desired.

Having described my invention, what I claim as new, and desire to secure by Letters Patent, is—

1. I claim the rake-guide rail N' and arch S' , when attached to the main frame by a bolt in front of the cutting apparatus and another bolt behind the said cutting apparatus, and without any connection with the platform, substantially as described and shown.

2. I claim, in combination with the internal gear-wheel J and its driving-pinion M , the pitman K and rake Q' , substantially as and for the purpose set forth.

3. The combination or arrangement of the sector-plate C , curved standard D , and standard E , substantially as described.

WM. N. WHITELY, JR.
